RAILWAY SIGNALING APPARATUS

John M. Pelikan, Pittsburgh, Pa., assignor to
The Union Switch & Signal Company, Swiss-
vale, Pa., a corporation of Pennsylvania

Application April 12, 1939, Serial No. 267,477

14 Claims. (Cl. 246—219)

My invention relates to railway signaling apparatus, and has particular reference to the organization of such apparatus into railway signaling systems of the type commonly termed automatic interlocking systems.

In systems of automatic interlocking hitherto proposed, priority of movement over the conflicting traffic portions of track is usually granted to the track on which a train first occupies an approach section adjacent the conflicting traffic portion, and the established track priority is maintained as long as that approach section is occupied, even though the approach section for the other track becomes occupied. While this system of establishing and maintaining track priority is satisfactory in many instances, such system is undesirable in the event that traffic movements over two conflicting tracks are so scheduled that trains from each track follow each other alternately over the conflicting traffic portions, and the volume of traffic is such that two or more trains may occupy each approach section concurrently. Accordingly, an object of my present invention is the provision in an automatic interlocking system, of novel and improved means whereby track priority is established when a train first enters an approach section, is maintained as long as that section is occupied and the other approach section remains unoccupied, but whenever both sections are concurrently occupied, traffic movements are then so controlled as to permit trains on each track to proceed alternately over the conflicting track portions.

Apparatus embodying my invention is particularly well adapted for, but not limited thereto, controlling the movements of trains on subway, elevated or surface systems where a large number of trains or individual cars are operated with very close headways.

Other objects and advantages of my invention will appear as the specification progresses.

I shall describe one form of apparatus embodying my invention, and shall then point out the novel features thereof in claims.

The accompanying drawing is a diagrammatic view showing a preferred form of apparatus embodying my invention.

Referring to the drawing, the reference character 2 designates a first stretch of railway track over which traffic normally moves in the direction indicated by the associated arrow in the diagram, and the reference character 3 designates a second stretch of track over which traffic normally moves in the direction indicated in the drawing by its associated arrow. The tracks 2

and 3 are so arranged that traffic movements over a portion of one track will conflict with traffic movements over a portion of the other track. As herein shown, track 3 converges into and joins track 2, but it will be understood, of course, that my invention is not limited to the particular track layout shown for the purpose of illustration.

The reference characters 2S and 3S designate railway traffic controlling signals, signal 2S being provided for track 2 and signal 3S being provided for track 3, each signal controlling traffic movements over its associated track toward the junction of the two tracks.

Tracks 2 and 3 are each provided in the usual manner with an approach section 2T or 3T, respectively, each terminating at the fouling point of the two tracks, that is, at the point at which traffic movements on the one track will interfere with traffic movements on the other. A control section 1T is also provided and includes the junction points of the two tracks, extending therefrom along each track so as to adjoin each approach section. Each of the sections is provided in the usual manner with a track circuit, relays 1TR, 2TR and 3TR being included in the track circuits for sections 1T, 2T and 3T, respectively. As indicated in the drawing, a spring switch is preferably located at the junction points of tracks 2 and 3 to permit traffic from either track to pass the junction point of such tracks.

The reference character FR designates a polarized signal selecting relay. Relay FR is energized with current of normal or reverse polarity over four circuits each of which will be pointed out hereinafter. At this time, however, it should be pointed out that when relay FR is energized with current of normal polarity, its contact member 4 is then operated to its normal position wherein normal polar contact 4—5 is closed, and that when relay FR is energized with current of reverse polarity, its contact member 4 is operated to its reverse position wherein reverse polar contact 4—6 is closed. The parts of relay FR are preferably so proportioned that whenever contact member 4 of relay FR is operated to one position by virtue of current of one polarity, the contact member will remain in that position until the winding of relay FR is energized by current of the other polarity to thereby operate contact member 4 to its other position.

The reference character 2HR designates a signal control relay provided for signal 2S, and the reference character 3HR designates a signal control relay provided for signal 3S. Each relay 2HR and 3HR is provided with a pick-up circuit

5

55

governed by relay FR, and which circuits will be pointed out in detail presently. At this time, however, it should be pointed out that the pick-up circuit for relay 2HR is selected to be completed whenever normal polar contact 4-5 of relay FR is closed, and that the pick-up circuit for relay 3HR is selected to be completed whenever reverse polar contact 4-6 of relay FR is closed. Relays 2HR and 3HR are each also provided with a stick circuit, and which circuits will be pointed out presently.

Signals 2S and 3S hereinbefore referred to as controlling traffic operating over tracks 2 and 3, respectively, are preferably of the same type, and may take any one of the many forms of railway signaling devices well known to the art. These signals, however, are herein shown as two-indication signals of the color light type, each comprising a green lamp G and a red lamp R. Signals 2S and 3S are normally dark, but as will appear presently, each signal is adapted to display a green or clear indication when its green lamp G is energized, and a red or restrictive indication when its red lamp R is energized. Each of the signals becomes lighted when the approach section of its associated track becomes occupied, and the particular indication displayed by such signal is determined according as its associated signal control relay is then picked up or released. For example, signal 3S is caused to display its clear indication when lamp G of that signal is energized over a circuit which may be traced from terminal B of a suitable source of current, such as a battery 31, through back contact 7 of relay 2TR, front contact 8 of relay 2HR, and the filament of lamp G of signal 2S to a midterminal C of battery 27, but it is readily apparent that when relay 2HR is released so that its front contact 8 is opened and its back contact 8 is closed, red lamp R is then energized to cause signal 2S to display its restrictive indication. The circuits whereby signal 3S is caused to display its respective clear or restrictive indication may be traced from terminal B through back contact 9 of relay 3TR, then through front contact 10 of relay 3HR and the filament of lamp G of signal 3S to terminal C, or through back contact 10 of relay 3HR and the filament of lamp R of signal 3S to terminal C. Battery 37, as shown, is preferably a split battery provided with two outside terminals B and N, respectively, and a midterminal C.

The reference characters 2LSR and 3LSR designate traffic locking relays associated with signal control relays 2HR and 3HR respectively. Relay 2LSR is normally energized over a stick circuit which passes from terminal B through back contact 11 of relay 2HR, front contact 12 of relay 2LSR, and the winding of relay 2LSR to terminal C. Relay 3LSR is normally energized over a stick circuit which passes from terminal B through back contact 13 of relay 3HR, front contact 14 of relay 3LSR and the winding of 3LSR to terminal C. Relays 2LSR and 3LSR are also each provided with a pick-up circuit, and which circuits will be pointed out presently.

The reference characters 15 and 16 designate manually operable circuit controllers, each of which is herein shown in the form of a push button. Push button 15 is preferably located adjacent signal 2S, while push button 16 is preferably located adjacent signal 3S. The function of these push buttons will be made clear as the specification progresses.

Having thus described the apparatus embodying my invention, I shall now explain its operation. I shall first assume that the apparatus is in its normal condition as shown in the drawing. In this condition of the apparatus, relays 1TR, 2TR, 3TR, 2LSR and 3LSR are energized, relays 2HR and 3HR are deenergized, relay FR is also deenergized and its normal polar contact 4-5 is closed, and signals 2S and 3S are in their darkened condition.

With the apparatus in the condition just described, I shall first assume that a train operating on track 2 enters section 2T in approaching the junction with track 3, with the result that relay 2TR is shunted and releases. Relay 2TR in releasing closes its back contact 17 and thereby completes a first energizing circuit for relay FR, which circuit passes from terminal B through back contact 17 of relay 2TR, front contact 18 of relay 3TR and the winding of relay FR to terminal C. As may readily be seen from an inspection of the drawing, this first circuit for relay FR will be completed whenever approach section 2T becomes or is occupied during the interval that the other approach section 3T is unoccupied. I shall term the current supplied to relay FR over its first circuit by virtue of the electromotive force across terminals B and C of battery 37, as being current of normal polarity. With relay FR now energized with current of normal polarity, its contact member 4 remains in its normal position to close normal contact 4-5 and thereby select relay 2HR for energization. With relay 2TR released and contact 4-5 of relay FR closed, relay 2HR becomes picked up over its previously mentioned pick-up circuit, which may be traced from terminal B through front contact 19 of relay 1TR, normal polar contact 4-5 of relay FR, front contact 20 of relay 3LSR, back contact 21 of relay 2TR and the winding of relay 2HR to terminal C. Also, with relay 2HR picked up to close its front contact 8, and with relay 2TR released so that its back contact 7 is closed, the circuit previously traced for lamp G of signal 2S is now completed whereby that signal is caused to display its clear indication.

Relay 2HR in picking up closes its front contact 25 to thereby complete its previously mentioned stick circuit, which passes from terminal B through contact 22 of push button 16, contact 23 of push button 15, front contact 24 of relay 1TR, front contact 25 of relay 2HR, back contact 21 of relay 2TR and the winding of relay 2HR to terminal C. Relay 2HR in picking up also opens its back contact 11, thereby opening the previously traced stick circuit for relay 2LSR with the result that relay 2LSR releases, but at this time this action of relay 2LSR serves no useful purpose.

With signal 2S now displaying its clear indication, the train on track 2 is signaled to proceed across the junction of tracks 2 and 3. When the train enters section 1T, relay 1TR is shunted and releases to open its front contacts 19 and 24, thereby opening respectively the previously traced pick-up and stick circuits for relay 2HR, with the result that relay 2HR releases and closes its back contact 8 to control signal 2S to its restrictive indication. This indication will be displayed by signal 2S until such time as the train vacates section 2T and relay 2TR picks up to open its back contact 7, whereupon signal 2S becomes dark.

The previously mentioned pick-up circuit for relay 2LSR also is completed when relay 2HR

10

15

20

25

30

35

40

45

55

60

65

70

75

releases, so that relay 2LSR is picked up and closes its front contact 12 to thereby complete its stick circuit, which circuit holds that relay normally energized. This pick-up circuit for 5 relay 2LSR may be traced from terminal B through back contact 11 of relay 2HR, back contact 29 of relay 1TR (which contact has in multiple therewith contact 30 of push button 16), and the winding of relay 2LSR to terminal C.

10 Then when the train vacates section 1T and relay 1TR picks up, the apparatus is restored to its normal condition.

I shall now assume that, with the apparatus in the condition just described, a train operating on track 3 enters approach section 3T so that relay 3TR is shunted and releases to complete at its back contact 18 a second energizing circuit for relay FR. This second circuit may be traced from terminal N through front contact 28 of relay 2TR, back contact 18 of relay 3TR and the winding of relay FR to terminal C, and this circuit, as can readily be seen from an inspection of the drawing, will be completed whenever approach section 3T becomes or is 20 occupied during the interval that the other approach section 2T is unoccupied. The polarity of current now supplied to relay FR by virtue of the electromotive force across terminals N and C of battery 37, I shall term reverse polarity.

30 With relay FR energized by current of reverse polarity, its polar armature 4 is shifted to its reverse position wherein reverse polar contact 4-6 is closed to complete the previously mentioned pick-up circuit for relay 3HR (which passes from terminal B through front contact 13 of relay 1TR, reverse polar contact 4-6 of relay FR, front contact 31 of relay 2LSR, back contact 32 of relay 3TR and the winding of relay 3HR to terminal C), so that relay 3HR picks up, 40 thereby opening its back contacts 10 and 13 and closing its front contacts 16 and 33. The closing of front contact 33 of relay 3HR completes its previously mentioned stick circuit, which passes from terminal B through contact 45 22 of push button 16, contact 23 of push button 15, front contact 24 of relay 1TR, front contact 33 of relay 3HR, back contact 32 of relay 3TR, and the winding of relay 3HR to terminal C. The closing of front contact 10 of relay 3HR 50 completes the previously mentioned energizing circuit for lamp G of signal 3S whereupon that signal displays its clear indication, and the opening of back contact 13 of relay 3HR interrupts the stick circuit for relay 3LSR whereupon 55 the latter relay releases.

When the train operating on track 3 enters section 1T in response to the clear indication displayed by signal 3S, relay 1TR is released to open at its front contacts 19 and 24, respectively, 60 the previously traced pick-up and stick circuits for relay 3HR. Relay 3HR is thus deenergized and releases to close its back contacts 10 and 13, back contact 18 of relay 3HR completing the energizing circuit for lamp R of signal 3S whereupon that signal displays its restrictive indication until such time as the train vacates section 3T and relay 3TR becomes reenergized to open its back contact 9. The closing of back contact 13 of relay 3HR completes the previously mentioned pick-up circuit for relay 3LSR, and which circuit may be traced from terminal B through back contact 13 of relay 3HR, back contact 35 of relay 1TR (which contact has in multiple therewith contact 36 of push button 15), and 70 the winding of relay 3LSR to terminal C. Relay 75

3LSR now picks up to close its front contact 14 and thereby complete its stick circuit which holds that relay normally energized. Then, when the train vacates section 1T, relay 1TR picks up. Relays 1TR, 2TR, 3TR, 2LSR and 3LSR are now 5 energized, relays 2HR and 3HR are deenergized, relay FR is also deenergized, and since it was last energized by current of reverse polarity, reverse polar contact 4-6 of relay FR is now closed. 10

I shall now explain the manner in which the apparatus embodying my invention functions to control signals 2S and 3S so that trains on each track are permitted to alternately enter the control section 1T when both approach sections are 15 concurrently occupied. To illustrate the above operation, I shall assume that with the apparatus in the condition above described, a first train, operating on track 2, enters approach section 2T, and that prior to the time that such first 20 train enters control section 1T a second train, operating on track 3, enters approach section 3T and a third train, operating on track 2, enters approach section 2T. Thus, both approach sections 2T and 3T are concurrently occupied by at 25 least one train, section 2T now being occupied by two trains and section 3T being occupied by one train.

The entrance of the first train on section 2T will select signal 2S to display its clear indication 30 to thereby establish priority for track 2, in the manner pointed out in detail heretofore. That is, the release of relay 2TR establishes the previously mentioned first circuit for relay FR, whereupon that relay becomes energized by current of normal polarity to shift its polar contact member 4 to its normal position. In this position of contact member 4, the normal polar contact 4-5 of relay FR is closed to complete the pick-up circuit for relay 2HR, whereupon relay 2HR 40 picks up to control signal 2S to its clear indication. Relay 2HR also opens the stick circuit for relay 2LSR so that the latter relay releases. 45

The entrance of the second train upon section 3T will now control the associated signal to prevent traffic movements on track 3 from interfering or conflicting with the priority of movement established for track 2, and will also condition signal selection relay FR so that priority of traffic movement will be established for track 3 50 after the first train has operated through control section 1T. Relay FR is conditioned at this time for the above mentioned operation over a third energizing circuit, which may be traced from terminal N through front contact 26 of relay 3LSR, back contact 27 of relay 2LSR, back contact 28 of relay 2TR, back contact 18 of relay 3TR, and the winding of relay FR to terminal C. As is readily apparent from an inspection of the drawing, this third circuit will be completed 55 whenever approach section 3T becomes or is occupied during the interval that the apparatus is controlled by traffic conditions upon track 2 to cause signal 2S to display its clear indication and thereby grant priority of traffic movement 60 to track 2. The current supplied to relay FR over its third circuit is of reverse polarity, with the result that relay FR shifts its polar contact member 4 to its reverse position. In this position of contact member 4, normal polar contact 4-5 is opened to interrupt at that point the pick-up circuit for relay 2HR (which is now retained energized over its stick circuit), and reverse polar contact 4-6 is now closed to select and prepare the pick-up circuit for relay 70 75

3HR. This latter pick-up circuit, however, is open at front contact 31 of the traffic locking relay 2LSR, which relay was released, as was pointed out previously, in response to the energization of signal control relay 2HR, so that traffic conditions upon section 3T will not at this time interfere with the previously established priority for track 2.

The releasing of relay 3TR in response to the entrance of the second train upon section 3T will also complete the energizing circuit for lamp R of signal 3S, with the result that signal 3S is caused to display its restrictive indication to track 3.

15 The entrance of the third train upon approach section 2T will have no effect upon the operation of the apparatus at this time, since the first train is assumed to be still entirely within section 2T, and the apparatus has already established traffic priority to track 2. However, when the first train vacates section 2T, the presence of the third train upon section 2T will then cause signal 2S to display its lighted restrictive indication, as will be made clear presently.

25 The entrance of the first train upon control section 1T in response to the clear indication displayed by signal 2S, results in relay 1TR releasing to open the stick circuit for relay 2HR, whereupon the latter relay releases. Relay 2HR in re-

30 leasing completes the energizing circuit for lamp R of signal 2S to cause that signal to display its restrictive condition, and also completes the pick-up circuit for relay 2LSR. Relay 2LSR then picks up to close its stick circuit at its front contact 12, and

35 also closes its front contact 31 to prepare the pick-up circuit for relay 3HR, but this latter pick-up circuit is now open at front contact 19 of relay 1TR so that relay 3HR at this time remains released. At this time, therefore, both ap-

40 proach sections 2T and 3T are occupied, control section 1T is also occupied, and signals 2S and 3S display their respective restrictive indications to prevent traffic movements from the approach sections into the occupied control section. Signal

45 2S continues to display its lighted restrictive indication after the first train has vacated section 2T, since it has been assumed that section 2T is now occupied by the third train, and with relays 2TR and 2HR released, signal 2S is caused

50 to display its lighted restrictive indication.

When the first train vacates section 1T, the apparatus then operates to establish traffic priority to track 3T so that the second train, operating on track 3T, is permitted to operate past

55 the conflicting track portions of tracks 2 and 3. Furthermore, the apparatus also functions to condition the signal selection relay FR so that traffic priority will again be established for track 2 after the train on track 3 has operated through

60 the control section 1T. The above mentioned operation of the apparatus is effected by the reenergization of relay 1TR in response to the first train vacating section 1T, since front contact 19 of relay 1TR then closes to complete the pick-

65 up circuit for relay 3HR. The energization of relay 3HR controls signal 3S to its clear indication to establish traffic priority to track 3, and also controls traffic locking relay 3LSR to its released condition by opening the stick circuit of

70 the latter relay. The releasing of relay 3LSR now establishes a fourth energizing circuit for relay FR to thereby condition the latter relay so that priority of traffic movement will again be established for track 2 after the train on track

75 3 operates past the control section 1T. This

fourth energizing circuit for relay FR passes from terminal B through back contact 34 of relay 3LSR, front contact 21 of relay 2LSR, back contact 28 of relay 2TR, back contact 18 of relay 3TR, and the winding of relay FR to terminal C. As may readily be seen from an inspection of the drawing, this fourth circuit will be completed whenever approach section 2T becomes or is occupied during the interval that the apparatus is conditioned by traffic conditions on track 3 to cause signal 3S to display its clear indication and thereby establish traffic priority to track 3. The current now supplied to relay FR over its fourth circuit is of normal polarity, so that relay FR now operates its contact member 4 to its normal position, thereby opening reverse polar contact 4-6 of relay FR to interrupt at that point the pick-up circuit for relay 3HR (which relay is now retained energized over its stick circuit), and closing normal polar contact 4-5 to select and prepare the pick-up circuit for relay 2HR. This latter relay, however, remains released since its pick-up circuit is open at front contact 20 of traffic locking relay 3LSR, which relay was in turn released in response to the energization of relay 3HR so that traffic conditions upon track 2 will not at this time effect the traffic priority established for track 3.

When the second train enters section 1T in response to the clear indication displayed by signal 3S, relay 1TR becomes released and opens the stick circuit for relay 3HR. Relay 3HR then releases to control signal 3S to display its restrictive indication, and also completes the pick-up circuit for relay 3LSR, whereupon the latter relay picks up to close its front contact 14 and thereby complete its stick circuit which holds that relay normally energized. The closing of front contact 20 of relay 3LSR does not at this time complete the pick-up circuit for relay 2HR, since this latter circuit is now open at front contact 19 of relay 1TR. Since it has been assumed that only one train is operating over track 3, it follows that when that train vacates section 3T, relay 3TR then picks up to open the energizing circuit for signal 3S and thereby control that signal to its darkened condition. It is readily apparent, however, that if section 3T is now occupied by another train, signal S then will be controlled to its lighted restrictive indication.

When the second train vacates section 1T, the apparatus will then be controlled so that traffic movements are permitted from section 2T into section 1T. This operation of the apparatus is effected when the second train vacates section 1T since relay 1TR then becomes reenergized and closes its front contact 19 to thereby complete the pick-up circuit for relay 2HR, whereupon relay 2HR picks up to control signal 2S to its clear indication to thereby establish priority of movement for track 2. The further operation of the apparatus in response to the third train entering and passing through control section 1T in response to the clear indication displayed by signal 2S under the above conditions, will be substantially similar to the operation of the apparatus first described for a single train operating along track 2, and further detailed explanation is deemed unnecessary.

From the foregoing description, it is readily apparent that when the control section and both approach sections are unoccupied, the entrance of a train upon either one of the approach sections causes the signal associated with that section to display its proceed indication to grant

priority of traffic movement to traffic operating upon that particular track. It is further apparent that when the apparatus is controlled by traffic conditions in either one of the approach sections so that priority is established for one track, the entrance of a train upon the approach section of the other track then causes the signal associated with the latter approach section to display its restrictive indication, thereby preventing any traffic movements on this other track from interfering or conflicting with the established priority of traffic movements. Furthermore, it is readily apparent that when each of the two approach sections is concurrently occupied by one or more trains, and the apparatus is conditioned to establish traffic priority to one track, the apparatus is so controlled by a train operating through the control section 1T in response to the established traffic priority as to establish traffic priority for the other track, regardless of the number of trains then occupying the track for which traffic priority first was established. It follows, therefore, that priority in traffic movement across the conflicting portions of track is established for either track whenever its associated approach section is entered first by a train; that the established priority is maintained as long as that approach section is occupied and the other approach section is unoccupied; and that whenever both track sections are concurrently occupied, traffic movements are then so controlled as to permit trains on each track to proceed alternately across the conflicting portions of track.

Push buttons 15 and 16, previously referred to as being located adjacent signals 2S and 3S, respectively, are provided to permit the track priority established by traffic conditions upon tracks 2 and 3 to be manually controlled to a different priority. Such manual control of the track priority may be desirable when, after the apparatus has been automatically controlled to establish traffic priority for one track, it is desired that a train on the other track be granted priority of movement through the control section. In this event, a trainman of the train for which priority of traffic movement is desired may then operate the push button located adjacent the signal controlling traffic over the track upon which priority is desired, thereby cancelling the established priority and causing the apparatus to control signals 2S and 3S to effect the desired new priority. For example, assume that both sections 2T and 3T are occupied and the apparatus is conditioned to grant priority in traffic movement to track 2. Under the conditions just assumed, signal 2S is displaying its clear indication and signal 3S is displaying its restrictive indication. Also under these conditions, relay FR is controlled in the manner pointed out in detail heretofore so that reverse polar contact 4-6 is closed to condition the apparatus to establish priority in traffic movement to track 3 after a train moves from section 2T through section 1T.

Under the above assumed conditions, if it is desired to operate a train on track 3 across section 1T prior to permitting the train on track 2 to operate across section 1T, the trainman of the train on track 3 may then operate push button 16 located adjacent signal 3S. This operation of push button 16 opens contact 22 of push button 16 interposed in the stick circuit for relay 2HR, whereupon that relay becomes released to control signal 2S to its restrictive indication, thereby cancelling the established traffic priority effected by traffic operating over tracks 2 and 3.

Furthermore, the actuation of push button 16 also closes contact 30 of that push button to thereby close the pick-up circuit for relay 2LSR, whereupon relay 2LSR becomes energized to close its front contact 12 and thereby complete its stick circuit, and also closes its front contact 31 which now completes the pick-up circuit for relay 3HR. Relay 3HR in picking up controls signal 3S to its clear indication to thereby establish the desired traffic priority for track 3, whereby the train on track 3 is permitted to cross section 1T prior to the train on track 2 crossing that control section. Relay 3HR in picking up also opens the stick circuit for relay 3LSR, whereupon the latter relay releases to complete the previously traced fourth energizing circuit for relay FR, since both approach sections 2T and 3T are now occupied and the apparatus is conditioned to establish traffic priority to track 3.

With the apparatus now controlled to the desired priority, operation of the train on track 3 through control section 1T will automatically establish traffic priority to track 2 in the manner previously pointed out in detail.

Similar control of signals 2S and 3S to grant priority to track 2 when both approach sections are occupied and the apparatus is conditioned to establish traffic priority to track 3, may be effected by operating push button 15, as is obvious from an inspection of the drawing.

From the foregoing, it can be seen that push buttons 15 and 16 provide means whereby the traffic priority established by traffic conditions in tracks 2 and 3 may be manually controlled to establish a different traffic priority.

While I have described but a few of the operations of the apparatus embodying my invention, it is readily apparent as to how the apparatus will function for any possible train movement.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In an automatic railway interlocking system, in combination, two stretches of railway track each having traffic normally operating in but a single direction thereover, said tracks being so arranged that traffic movements over a portion of either track will conflict with traffic movements over a portion of the other track, said two tracks being provided with a common control section, said control section including the track portions of each track over which traffic movements interfere with traffic movements on the other track, each said track also being provided with an approach section located in approach of said control section, each said approach section being provided with a signal governing traffic movements from the associated approach section into said control section, each said approach section having a signal control relay governing the associated signal of that section, a signal selecting relay operable to a first or to a second position, circuit means responsive to traffic conditions in said control section for controlling each of said signal control relays, said circuit means being governed by said signal selecting relay and being effective to control a first or a second of said signal control relays according as said signal selecting relay is in its respective first or second position, means responsive to

traffic conditions in each of said approach sections and effective whenever either one of the approach sections becomes occupied during the interval that the other approach section is unoccupied for controlling the position of said signal selecting relay to select the signal control relay associated with said one approach section for control by said circuit means, and means responsive to traffic conditions in both said approach sections, operative whenever both said approach sections are concurrently occupied and one of said two signal control relays is controlled, for controlling the position of said signal selecting relay to select the signal control relay of the other approach section for control by said circuit means, whereby alternate traffic movements from each approach section through said control section are permitted when each approach section is concurrently occupied irrespective of the number of trains in each of said approved sections.

2. In an automatic railway interlocking system, in combination, two stretches of railway track each having traffic normally operating in but a single direction thereover, said tracks being so arranged that traffic movements over a portion of either track will conflict with traffic movements over a portion of the other track, said two tracks being provided with a common control section, said control section including the track portions of each track over which traffic movements interfere with traffic movements on the other track, each said track also being provided with an approach section located in approach of said control section, each said approach section being provided with a signal governing traffic movements from the associated approach section into said control section, means responsive to traffic conditions in said approach sections and effective whenever either one of said approach sections is occupied and the other approach section is unoccupied for controlling the signal associated with said one approach section to permit traffic movements from said one section through said control section, and means responsive to traffic conditions in both said approach sections, operative whenever both said approach sections are occupied and neither one of said signals is controlled to permit traffic movements through said control section, for rendering the other signal capable of being controlled to permit traffic movements from its associated approach section into said control section, said last mentioned means being governed by traffic conditions in said control section and being effective to permit traffic movements alternately from each approach section through said control section when both said approach sections are concurrently occupied.

3. In an automatic railway interlocking system, in combination, two stretches of railway track each having traffic normally operating in but a single direction thereover, said tracks being so arranged that traffic movements over a portion of either track will conflict with traffic movements over a portion of the other track, said two tracks being provided with a common control section, said control section including the track portions of each track over which traffic movements interfere with traffic movements on the other track, each said track also being provided with an approach section located in approach of said control section, each said approach section being provided with a signal governing traffic movements from the associated approach section into said control section, a control relay

for each signal, a traffic locking relay for each signal governed by the associated control relay, a signal selecting relay operable between a first and a second position, control means for energizing each control relay governed by the traffic locking relay of the other control relay, said control means being responsive to traffic conditions in the associated approach and in said control section and being selected to energize a first or the second of said control relays according as said signal selecting relay is in its respective first or second position, circuit means responsive to traffic conditions in said approach sections, operative whenever either one of said approach sections is occupied and the other section is unoccupied, for causing said signal selecting relay to operate to its particular position wherein the control relay of said one approach section is selected for energization by said control means, and other circuit means governed by said traffic locking relays and cooperating with the first mentioned circuit means, effective whenever both approach sections are occupied and either one of said control relays is energized, for causing said signal selecting relay to operate to its particular position wherein the other one of said control relays is selected for energization by said control means.

4. In an automatic railway interlocking system, in combination, two stretches of railway track each having traffic normally operating in but a single direction thereover, said tracks being so arranged that traffic movements over a portion of either track will conflict with traffic movements over a portion of the other track, said two tracks being provided with a common control section, said control section including the track portions of each track over which traffic movements interfere with traffic movements on the other track, each said track also being provided with an approach section located in approach of said control section, an approach track relay for each approach section and a control track relay for said control section, a signal for each approach section, a signal control relay for each approach section for controlling the associated signal, a polarized relay operable to one position or to another position, a pick-up circuit for each signal control relay governed by the other signal control relay and including a front contact of said control track relay and a back contact of the associated approach track relay, said pick-up circuits each being governed by said polarized relay and being effective to energize one or the other of said signal control relays when and only when said polarized relay is in its respective one or its other position, a stick circuit for each signal control relay including a front contact of said control track relay and a back contact of the associated approach track relay, circuit means governed by said approach track relays, operative whenever either one of said approach sections is occupied and the other approach section is unoccupied, effective to operate said polarized relay to its one or its other position according as one or the other of said approach sections is then occupied, other circuit means governed by said signal control relays and cooperating with the first mentioned circuit means, operative whenever both said approach sections are occupied and either one of said signal control relays is energized, for operating said polarized relay to its particular position wherein the pick-up circuit for the other one of said signal control relays is pre-

pared, whereby control of said signals is established to permit traffic movements alternately from each approach section through said control section in the event that both approach sections are concurrently occupied irrespective of the number of trains in each approach section.

5. In an automatic railway interlocking system, in combination, two stretches of railway track each having traffic normally operating in 10 but a single direction thereover, said tracks being so arranged that traffic movements over a portion of either track will conflict with traffic movements over a portion of the other track, said two tracks being provided with a common 15 control section, said control section including the track portions of each track over which traffic movements interfere with traffic movements on the other track, each said track also being provided with an approach section located in approach 20 of said control section, an approach track relay for each approach section and a control track relay for said control section, a signal for each approach section, a signal control relay for each signal, a signal selecting relay operable to 25 one or another of two positions, a pick-up circuit for each signal control relay governed by the other signal control relay and by the associated approach track relay and said control track relay, said pick-up circuits being further 30 governed by said signal selecting relay in such manner that one signal control relay will be energized only if said signal selecting relay is in its one position and the other signal control relay will be energized only if said signal selecting 35 relay is in its other position, a stick circuit for each signal control relay governed by the associated approach track relay and said control track relay, circuit means governed solely by said approach track relays and effective whenever either one of said approach sections is 40 occupied and the other approach section is unoccupied for causing said signal selecting relay to operate to its particular position wherein the pick-up circuit of the associated signal control 45 relay is conditioned to energize that signal control relay, and other means governed by said signal control relays and cooperating with said circuit means whenever both approach sections are occupied and either one of said signal control 50 relays is energized, for causing said signal selecting relay to operate to its particular position wherein the pick-up circuit of the other one of said signal control relays is conditioned to energize said other signal control relay, 55 whereby trains are controlled by said signals for alternate movements from each track through said control section whenever both approach sections are concurrently occupied irrespective of the number of trains occupying each approach 60 section.

6. In an automatic railway interlocking system, in combination, two stretches of railway track arranged in such manner that traffic movements over a portion of either track will conflict with traffic movements over a portion of the other track, a control section common to said two tracks and including the conflicting traffic portions of such tracks, two signals one for each of said tracks for governing traffic over the conflicting portion of the associated track, an approach section for each signal, and means responsive to traffic conditions in said approach sections and controlled by traffic movements through said control section for automatically 65 controlling said signals to permit alternate traffic 70 movements from said approach sections when such sections are concurrently occupied irrespective of the number of trains occupying each of said approach sections, and manually operable means for modifying the control exerted by said circuit means over said signals whereby to permit successive movements from either of said approach sections when such approach sections are concurrently occupied.

7. In an automatic railway interlocking system, in combination, two stretches of railway track arranged in such manner that traffic movements over a portion of either track will conflict with traffic movements over a portion of the other track, a control section common to said two tracks and including the conflicting traffic portions of such tracks, two signals one for each of said tracks for governing traffic over the conflicting portion of the associated track, an approach section for each signal, and means responsive to traffic conditions in said approach sections and automatically controlled by traffic movements through said control section for alternately clearing first one and then the other of said two signals whereby to permit traffic movements alternately from first one and then the other of said two approach sections when such sections are concurrently occupied regardless of the number of trains occupying each of said approach sections. 25

8. In an automatic railway interlocking system, in combination, two stretches of railway track arranged in such manner that traffic movements over a portion of either track will conflict with traffic movements over a portion of the other track, a control section common to said two tracks and including the conflicting traffic portions of such tracks, two signals one for each of said tracks for governing traffic over the conflicting portion of the associated track, an approach section for each signal, and means responsive to traffic conditions in said approach sections and automatically controlled by traffic movements through said control section for alternately clearing first one and then the other of said two signals whereby to permit traffic movements alternately from first one and then the other of said two approach sections when such sections are concurrently occupied regardless of the number of trains occupying each of said approach sections. 30

9. In an automatic railway interlocking system, in combination, two stretches of railway track arranged in such manner that traffic movements over a portion of either track will conflict with traffic movements over a portion of the other track, a control section common to said two tracks and including the conflicting traffic portions of such tracks, two signals one for each of said tracks for governing traffic over the conflicting portion of the associated track, an approach section for each signal, and means responsive to traffic conditions in said approach sections for clearing the one signal associated with the one of said two approach sections first to become occupied by a train and automatically controlled by traffic movements through said control section for alternately clearing said two signals to permit trains to move alternately from each approach section through said control section when both approach sections are concurrently occupied. 45

10. In an automatic railway interlocking system, in combination, two stretches of railway track arranged in such manner that traffic movements over a portion of either track will conflict with traffic movements over a portion of the other track, a control section common to said two tracks and including the conflicting traffic portions of such tracks, two signals one for each of said tracks for governing traffic over the conflicting portions of the associated track, an approach section for each signal, circuit means responsive to traffic conditions in said approach sections and automatically controlled by traffic movements through said control section for controlling said signals to permit alternate traffic movements from said approach sections when such sections are concurrently occupied irrespective of the number of trains occupying each of said approach sections, and manually operable means for modifying the control exerted by said circuit means over said signals whereby to permit successive movements from either of said approach sections when such approach sections are concurrently occupied. 55

11. In an automatic railway interlocking system, in combination, two stretches of railway track arranged in such manner that traffic movements over a portion of either track will conflict with traffic movements over a portion of the other track, a control section common to said two tracks and including the conflicting traffic portions of such tracks, two signals one for each of said tracks for governing traffic over the conflicting portion of the associated track, an approach section for each signal, and means responsive to traffic conditions in said approach sections and controlled by traffic movements through said control section for automatically 60 controlling said signals to permit alternate traffic 65 movements from said approach sections when such sections are concurrently occupied irrespective of the number of trains occupying each of said approach sections, and manually operable means for modifying the control exerted by said circuit means over said signals whereby to permit successive movements from either of said approach sections when such approach sections are concurrently occupied. 70

- such tracks, two signals one for each of said tracks for governing traffic over the conflicting portion of the associated track, an approach section for each signal, circuit means responsive to traffic conditions in said approach sections for clearing the one signal associated with the one of said two approach sections first to become occupied by a train and automatically controlled by traffic movements through said control section for alternately clearing said two signals to permit trains to move alternately from each approach section through said control section when both approach sections are concurrently occupied, and manually operable means for modifying the control exerted by said circuit means over said two signals whereby to permit successive movements from either of said two approach sections when such approach sections are concurrently occupied.
11. In an automatic railway interlocking system, in combination, two stretches of railway track arranged in such manner that traffic movements over a portion of either track will conflict with traffic movements over a portion of the other track, a control section common to said two tracks and including the conflicting traffic portions of such tracks, two signals one for each of said tracks for governing traffic over the conflicting portion of the associated track, an approach section for each signal, circuit means responsive to traffic conditions in said approach sections for clearing the one signal associated with the one of said two approach sections first to become occupied by a train and automatically controlled by traffic movements through said control section for alternately clearing said two signals to permit trains to move alternately from each approach section through said control section when both approach sections are concurrently occupied, and manually operable means effective when both of said approach sections are occupied and either one of said two signals is cleared by said circuit means for setting that one signal to stop and for clearing the other of said two signals.
12. In an automatic railway interlocking system, in combination, two stretches of railway track arranged in such manner that traffic movements over a portion of either track will conflict with traffic movements over a portion of the other track, a control section common to said two tracks and including the conflicting portions of such tracks, two signals one for each of said tracks for governing traffic over the conflicting portion of the associated track, two control relays one for each signal, an approach section for each signal, signal selecting means effective to select for control one or the other of said two control relays, means responsive to traffic conditions in said approach sections for controlling said signal

selecting means to select the one of said two control relays associated with the signal of the section first to become occupied by a train and automatically controlled by traffic movements through said control section for controlling said signal 5 selecting means to select said two control relays alternately, whereby trains from first one and then the other of said two approach sections alternately are permitted to proceed through said control section when both said approach sections are occupied.

13. In an automatic railway interlocking system, in combination, two stretches of railway track arranged in such manner that traffic movements over a portion of either track will conflict with traffic movements over a portion of the other track, a control section common to said two tracks and including the conflicting portions of such tracks, two signals one for each of said tracks for governing traffic over the conflicting portion 15 of the associated track, two control relays one for each signal, an approach section for each signal, a polarized signal selecting relay operable between a first position and a second, circuit means controlled by said polarized relay for selecting a first or a second of said two signal control relays for control according as said polarized relay is in its first or second position, and other circuit means responsive to traffic conditions in said approach sections for operating said polarized relay to its particular position wherein is selected the one of said two control relays associated with the signal of the approach section first to become occupied and controlled by traffic movements through said control section for reversibly operating said polarized relay to select said two control relays alternately, whereby alternate traffic movements from first one and then the other of said two approach sections are permitted when such sections are concurrently occupied.

14. A railway interlocking system of the class wherein signals governing traffic movements over two tracks having conflicting traffic portions are alternately cleared automatically by traffic movements over the conflicting portions of such tracks when approach sections provided for each track are concurrently occupied, characterized by the provision in such system of a polarized signal selecting relay reversibly operated by circuit means responsive to traffic conditions in the said approach sections and in said conflicting traffic portions of said two tracks, and controlling circuit means for selecting one or the other of said two signals to be cleared according as said polarized relay is in one or another of its two positions.

JOHN M. PELIKAN.
